US00D578194S

(12) **United States Design Patent**
DeFouw

(10) **Patent No.:** **US D578,194 S**
(45) **Date of Patent:** **** Oct. 7, 2008**

(54) **GAS FIREPIT**

(75) Inventor: **Douglas J. DeFouw**, Moore, SC (US)

(73) Assignee: **Agio International Company, Limited**,
East Kowloon, Hong Kong (CN)

(**) Term: **14 Years**

(21) Appl. No.: **29/288,663**

(22) Filed: **Jun. 19, 2007**

(51) **LOC (8) Cl. 23-03**

(52) **U.S. Cl. D23/343**

(58) **Field of Classification Search** D23/332-350;
126/25 R, 37 B, 41 R, 50, 506, 512-513,
126/519, 543, 304 R, 305-306; 264/139,
264/221; 428/34.5, 70; 431/125, 126, 253;
99/339, 340, 357

See application file for complete search history.

(74) *Attorney, Agent, or Firm*—Williams Mullen; M. Bruce Harper

(57) **CLAIM**

The ornamental design for a gas firepit, as shown and described.

DESCRIPTION

FIG. 1 is a perspective view;

FIG. 2 is a side view;

FIG. 3 is a top view with the lid;

FIG. 4 is a bottom view;

FIG. 5 is an exploded view; and,

FIG. 6 is a top view without the lid.

The broken line showing in FIG. 5 is included for illustrative purposes and forms no part of the claimed design.

1 Claim, 5 Drawing Sheets
